UNITED STATES PATENT OFFICE.

WILLIAM P. QUENTELL, OF KANSAS CITY, MISSOURI, ASSIGNOR TO THE AMERICAN TYPE FOUNDERS COMPANY, OF NEWARK, NEW JERSEY.

DESIGN FOR A FONT OF TYPE.

SPECIFICATION forming part of Design No. 24,683, dated September 17, 1895.

Application filed February 9, 1895. Serial No. 537,836. Term of patent 7 years.

To all whom it may concern:

Be it known that I, WILLIAM P. QUENTELL, a citizen of the United States, and a resident of Kansas City, Missouri, have invented a certain Design for a Font of Type, of which the following is a specification.

My design for a font of type is clearly illustrated in the accompanying typographical impression.

The general character of the design is that of a plain-letter font having heavy vertical lines and light cross-lines, the special features of the design being the particular characteristics of certain of the letters, as hereinafter set forth.

In the upper-case letters the right-hand line of the letter A is heavy and the left-hand line light, terminating in a square base projecting beyond the line. The cross-bar is made up of two light lines.

The vertical lines of the letter H are heavy and the cross-bar is composed of two light lines. One vertical line of the letter M is heavy and the other light, and one inclined line of the letter M is heavy and the other light. Both vertical lines of the letter N are light and the inclined line heavy. The vertical line of the letter T is heavy and the cross-line at the top light. The left-hand lines of the letters U and V are heavy and the right-hand lines light.

The other letters of the upper-case are in keeping with the peculiar features of the letters mentioned above, and the lower-case letters carry out the general features of design found in the upper-case.

I claim—

The design for a font of type as herein described and as shown in the accompanying typographical impression.

In testimony whereof I have signed my name to this specification in the presence of two subscribing witnesses.

WILLIAM P. QUENTELL.
